(57) **CLAIM**

The ornamental design for a motorcycle bag as shown and described.

DESCRIPTION

FIG. 1 is a front, left and top perspective view of a motorcycle bag, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right and top perspective view of the motorcycle bag in another state.

The broken lines shown in the drawings are included for the purpose of illustrating portions of the motorcycle bag that form no part of the claimed design.

1 Claim, 9 Drawing Sheets
